UNITED STATES PATENT OFFICE.

SWITS CONDÉ, OF OSWEGO, NEW YORK.

DESIGN FOR A KNITTED GARMENT.

SPECIFICATION forming part of Design No. 19,079, dated May 7, 1889.

Application filed March 18, 1889. Serial No. 303,779. Term of patent 7 years.

To all whom it may concern:

Be it known that I, SWITS CONDÉ, a citizen of the United States, residing at Oswego, in the county of Oswego and State of New York, 5 have invented and produced a new and original Design for Knitted Garments, of which the following is a specification, reference being had to the accompanying drawing, forming part thereof.

10 The drawing shows a front elevation of a blouse containing my design, one view being deemed sufficient to fully illustrate my design.

15 The leading feature of my design consists of a body for the garment, provided with a contracted band at the bottom of the garment.

20 *a* represents the body part of the garment, having ornamental lacing-cord *b* secured at the front *c* thereof, and the front bordered by plaits *d*. The bottom of the garment is composed of the contracted band *e*, formed of

horizontal stripes, causing the upper part of the garment to be gathered or ruffled and overhang the contracted band, forming a pleasing appearance.

What I claim is—

The design for garments herein shown and described, the same consisting of a contracted band, *e*, at the bottom of the garment, and the body part *a*, overhanging the contracted band *e* and provided with ornamental lacing-cord 30 *b*, substantially as set forth.

In testimony whereof I have hereunto signed my name, in the presence of two attesting witnesses, at Oswego, in the county of Oswego, in the State of New York, this 12th day 35 of March, 1889.

SWITS CONDÉ.
